UNITED STATES PATENT OFFICE

114,687

DESIGN FOR A WAFFLE IRON OR SIMILAR ARTICLE

August A. Propernick, Bridgeport, Conn., assignor to General Electric Company, a corporation of New York

Application September 1, 1938, Serial No. 79,663

Term of patent 14 years

To all whom it may concern:

Be it known that I, August A. Propernick, a citizen of the United States, residing at Bridgeport, in the county of Fairfield, State of Connecticut, have invented a new, original, and ornamental Design for a Waffle Iron or Similar Article, of which the following is a specification, reference being had to the accompanying drawing, forming a part thereof.

The drawing shows in Fig. 1 a side elevational view partly in section and in Fig. 2 a top plan view of a waffle iron embodying my new design.

I claim:

The ornamental design for a waffle iron or similar article, substantially as shown.

AUGUST A. PROPERNICK.
